UNITED STATES PATENT OFFICE.

CHARLES F. KRAUT, OF BALTIMORE, MARYLAND.

SAFETY-VALVE.

1,217,316.

Specification of Letters Patent.

Patented Feb. 27, 1917.

Application filed June 26, 1916. Serial No. 105,833.

To all whom it may concern:

Be it known that I, CHARLES F. KRAUT, a citizen of the United States, residing at Baltimore city, State of Maryland, have invented certain new and useful Improvements in Safety-Valves, of which the following is a specification.

The safety valve which is the subject-matter of the present application for patent is designed more particularly for use in connection with locomotive boilers, although it is not limited to such, and the invention has for its object to provide a safety valve of sufficient discharging capacity so that it will 15 not be necessary to equip the boiler with more than two of such valves.

The invention also has for its object to provide a safety valve having a minimum amount of lift, and to accomplish this without increasing the diameter of the valve. High lift valves are apt to discharge water when placed close to the boiler, and such location of the valve is imposed upon it in order that the locomotive may clear bridges, 25 tunnels, etc. A valve of sufficiently large diameter to overcome the high lift objection requires a heavy and expensive construction to withstand the spring pressure under which it labors, the greater the diameter of 30 the valve, the greater being the spring pressure necessary to hold the valve seated against the boiler pressure. Another objection to a large valve is that when adjusted for the blow back, the large area between 35 the outside circumference of the valve and the inside of the adjusting ring makes the valve slow to respond, considerable time elapsing before the valve pops, this being due to the fact that as the valve rises gradually admitting steam to the confining chamber, sufficient pressure must accumulate to raise the valve. This, with the great spring 40 tension to overcome, is very objectionable, as it causes the valve, as it lingers, to chatter or hum, to the great annoyance of the public.

A further object of the invention is to eliminate or reduce to a minimum the shock when the valve closes, thus preventing strain on the boiler and rapid wear of the valve. 50 The invention also has for its object to provide a novel and improved arrangement of parts whereby the structure is simplified and cheapened.

Various other objects and advantages of

the invention will be pointed out in the detailed description appearing hereinafter, and in order that the same may be better understood, reference is had to the accompanying drawings forming a part of this specification.

In the drawings, Figure 1 is a vertical section of the valve, and Figs. 2, 3 and 4 are cross-sections on the lines 2-2, 3-3 and 4-4, respectively, of Fig. 1.

Referring specifically to the drawings, 5 denotes the valve casing having a steam passageway 6 the inlet end of which is threaded for connection to the boiler. Over the top 10 of the valve casing is mounted a muffing dome 7 having in its top outlet perforations 8. In the passageway 6 is a guide 9 for the valve 10, said guide being spaced at its periphery from the wall of the passageway to form a relatively short discharge opening 15 to allow the steam to pass. The guide is integral with the valve casing and has a relatively shallow top recess 11 into which the lower end of the valve extends when it is seated. At the bottom of the guide is a spider composed of radial arms or webs 12 20 extending from the center of the guide to the wall of the passageway 6, and serving to strengthen the guide to withstand the heavy spring pressure. The downward or closing movement of the valve is cushioned 25 by the pressure trapped beneath it in the recess 11.

The relatively flat guide 9 in the upper end of the passageway 6 forms a steam chamber in the casing below the guide and 30 which extends in close proximity to the discharging point of the passageway or the valve seat. It has been found that the greater the volume of steam close to the valve seat the greater the discharge capacity 35 of the valve, therefore the relatively flat guide provides a chamber close to the valve seat that will contain a great volume of steam.

The valve 10 is in the form of a hollow 40 cylinder open at the top and closed at the bottom, with vent ducts 13 in the latter establishing communication between the recess 11 and the interior of the valve. The lower end of the valve is encircled externally by a ring 14 which is so positioned 45 that it seats on top of the valve casing over the discharge opening of the passage-

way 6, outlet opening being the annular space between the periphery of the guide 9 and the wall of the passageway. The ring 14 is threaded on the inside to screw on the 5 valve, the latter having lugs 15 on the outside which are threaded to receive and hold the ring.

Between the lugs 15 the valve body is reduced in diameter, whereby steam passageways 16 are produced. The valve body also 10 has lugs 17 against the bottom of which the ring 14 seats.

In the top of the valve casing 5 is an annular recess 18 having its inner surface screw-threaded to receive the adjusting ring 19, the latter rising from the top of the valve casing and its upper projecting end encircling the ring 14 when the valve 10 is seated. The outer periphery of the ring 14 15 is beveled inward as shown at 20 which forms a space 21 between the same and the inner periphery of the projecting portion of the ring 19. The ring 19 is adjustable up or down to vary the distance it projects from 20 the top of the valve casing and the area of the space 21.

The adjustment of the ring 14 is effected by a worm 22 meshing with a worm thread 23 on the periphery of the ring. The worm 30 is mounted in a transverse recess 24 in the valve casing 5, and is held against travel in the direction of its length by a set screw 25 threaded through the valve casing and having its inner end seating in an annular 35 groove 26 in the shank of the worm. The ends of the worm shank are squared for the application of a wrench or other tool for turning the same to effect the adjustment of the ring 14. The worm does not project 40 from the valve casing to interfere with other parts.

The set screw 25 when screwed in tight engagement with the portion of the worm in the groove 26, will effectually lock the 45 worm and the adjusting ring 19 in any adjusted position.

Formed integral with the top of the dome 7, at the center thereof, is an enlargement 27 through which is threaded the adjusting screw 28 of the valve spring 29. A lock nut 30 is provided for the screw. The valve spring is located on the inside of the valve 50 cylinder and is engaged at its ends by heads 31. The bottom head seats on the closed 55 lower end of the valve, and the top head seats against the inner end of the screw 28. The top head has a vent port 32 communicating with a vent outlet passageway 33 in the screw 28, said passageway opening 60 through the outer end of the screw to the atmosphere. Thus, it will be seen that if any pressure is trapped under the valve, it may escape to the atmosphere through the ducts 13, port 32 and passageway 33.

65 The upper end of the valve 10 is guided

by a cylindrical sleeve 34 into which it extends, said sleeve being formed integral with and depending from the top of the dome 7. The sleeve is spaced from the side of the dome and in this space are radial webs 35 70 extending between the sleeve and the side wall of the dome, and formed integral therewith. The bottom edges of the webs are flush with the bottom of the sleeve, and on said edges are mounted concentric and 75 spaced baffle rings 36, the same being connected at intervals by cross webs 37. The rings are fixed to the webs 35 by studs 38 on certain ones of the latter, and passing through apertures in corresponding cross webs 37, the studs being headed or riveted after being passed through the webs. The rings are in line with the outlet perforations 8.

The only portion of the valve 10 which is 85 exposed to the boiler pressure is that part of the ring 14 which seats over and closes the upper contracted end of the passageway 6, the reduction in the area of the passageway being produced by the guide 9. In view of 90 this restricted area exposed to the steam pressure, a much smaller valve spring may be employed for holding the valve seated against the boiler pressure. When the valve 95 pops the pressure escapes not only through the space 21, but also through the passageways 16, resulting in a quick action with a minimum valve lift.

The parts hereinbefore described are so 100 designed that the patterns can be made to form their own core, thus eliminating costly core making operations. The number of parts is reduced to a minimum, reducing the machining operations required, expediting the handling of the valve in the process of 105 manufacture, cheapening the cost, and resulting in economy in handling and in the purchase of repair parts. The worm 22 being accessible from the outside of the valve casing, the ring 19 may be readily adjusted 110 without removing the dome 7 or disturbing any other parts.

I claim:

1. In a safety valve, a casing having a steam passageway, and a muffling dome into 115 which the passageway opens, the outlet end of the passageway being of restricted area, and a valve having a removable external encircling ring at its lower end which seats over and closes said outlet end of the passageway, the body of said valve adjacent 120 said encircling ring being reduced in diameter to form steam passageways.

2. In a safety valve, a casing having a steam passageway, and a muffling dome into 125 which the passageway opens, the outlet end of the passageway being of restricted area, and a valve having a removable external encircling ring at its lower end which seats over and closes said outlet end of the pas- 130

sageway, the body of said valve adjacent to said encircling ring being reduced in diameter to form a series of lugs to which the encircling ring is secured and steam passageways between said lugs.

3. In a safety valve, a casing having a steam passageway, and a muffling dome into which the passageway opens, the outlet end of the passageway being of restricted area, 10 and a valve having a removable external encircling ring at its lower end which seats over and closes said outlet end of the passageway, the body of said valve adjacent to said encircling ring being reduced in diameter to form a series of lugs having screw-threaded outer faces and to which the encircling ring is secured and steam passageways between said lugs.

4. In a safety valve, a casing having a steam passageway and a muffling dome into which the passageway discharges, a relatively flat guide in the upper end of said passageway forming a steam chamber beneath the same and spaced from the walls thereof to form a relatively short restricted discharge opening, said guide being provided with a shallow top recess, a valve body having its lower end engaging on said recess, and a closing part on said valve body to close 30 said restricted discharge opening.

5. In a safety valve, a casing having a steam passageway and a muffling dome into which the passageway discharges, a relatively flat guide in the upper end of said passageway forming a steam chamber beneath the same and spaced from the walls thereof to form a relatively short restricted discharge opening, said guide being provided with a shallow top recess, a valve body 35 having its lower end engaging on said recess, and a closing part on said valve body to close said restricted discharge opening, that portion of the valve body which engages said shallow recess being provided with steam 40 escape openings.

6. In a safety valve, a casing having a steam passageway and a muffling dome into which the passageway discharges, a relatively flat guide in the upper end of said passageway forming a steam chamber beneath the same and spaced from the walls thereof to form a relatively short restricted 50 discharge opening, said guide being pro-

vided with a shallow top recess and connected integrally with said casing by radial webs which extend beneath said guide.

7. In a safety valve, a casing having a steam passageway and a muffling dome into which the passageway opens, a valve closing the outlet end of the passageway into the dome, a guide sleeve for the valve depending from the top of the dome, radial webs extending between the sleeve and the side of the dome, and baffle rings mounted on the bottom edges of the webs beneath the space between the sleeve and the side of the dome.

8. In a safety valve, a casing having a steam passageway provided with a valve-guide and a muffling dome into which the passageway opens, an integral central cylindrical wall depending from the top of said muffling dome and a valve provided with an apertured bottom which engages in said valve-guide and an elongated cylindrical extension whose upper end engages and is guided on the interior of said depending cylindrical wall, a closing spring for the valve inclosed in its elongated extension and the depending wall, and a screw for the spring adjustably mounted in the top of the dome and provided with a central passageway for relieving pressure in the spring chamber and from the valve-guide beneath said perforated bottom of the valve.

9. In a safety valve, a casing having a steam passageway and a muffling dome into which the passageway opens, a valve closing the outlet end of said passageway, an adjusting ring having a toothed periphery encircling said valve, a support for the ring upon which it is screwed, a worm mounted and housed in said casing, said worm being squared on each end and provided with an annular groove intermediate its ends, and a locking screw adjustably mounted in the wall of said casing in position to engage in said annular groove to prevent endwise movement of the worm and to serve as a lock for the worm and adjusting ring.

In testimony whereof I affix my signature in presence of two witnesses.
